UNITED STATES PATENT OFFICE.

GEORGE A. MCILHENNY, OF WASHINGTON, DISTRICT OF COLUMBIA.

HYDRAULIC MAIN FOR GAS-WORKS.

SPECIFICATION forming part of Letters Patent No. 282,345, dated July 31, 1883.

Application filed April 21, 1883. (No model.)

To all whom it may concern:

Be it known that I, GEORGE A. MCILHENNY, of the city of Washington and District of Columbia, have invented certain new and useful Improvements in Hydraulic Mains for Gas-Works; and I do hereby declare that the following specification, taken in connection with the drawings furnished and forming a part of the same, is a clear, true, and complete description of the several features of my invention.

Although some of my said improvements are applicable to retort-benches operated at ordinary temperatures, I have devised them with special reference to such as are worked at extraordinary high temperatures on the so-called "recuperative" system.

One portion of my invention consists in the combination of a hydraulic main having a tar-pocket at one side and extending throughout its length, ascension-pipes which enter through the bottom of the main from below, and a dip or sealing pipe which is pendent from the top of the main and surrounds the top of the ascension-pipe. Tar-pockets have heretofore been provided in hydraulic mains, but only in such as have the gas conducted from the retorts by outside ascension-pipes connecting with dip-pipes which enter through the top of the main and have their lower ends sealed, and, as heretofore organized, the contents of said pockets are so liable to harden by cooling that steam heating-jackets have been devised for keeping said contents at a desirable temperature to enable the removal thereof. As constructed and organized by me, the ascension-pipes leading directly from the retorts through the bottom of the main and adjacent to said pockets so heat the bottom of the main and the walls of the pocket as to not only secure the free flow and deposit of the tarry matters into said pocket, but enable them to be readily discharged or removed therefrom.

It is also well known that the ascension-pipes of retorts operated under extraordinarily high temperatures require more frequent clearing from more or less solid accumulations therein than when operated at ordinary temperatures, and that the clearing operation is performed by workmen standing on top of the hydraulic main; and another portion of my

invention relates to a particular construction of the hydraulic main, dip-pipe, dip-pipe lids, and the adjacent parts, whereby they are 55 economically constructed and more securely closed and more readily removed and replaced, thus saving much time at each opening and closing of a lid, which is a matter of special importance in view of the necessary increased 60 frequency of the clearing operation referred to.

In my prior Letters Patent No. 247,386, September 20, 1881, I show a lid, a screw, and a cross-bar, to which said screw is tapped; but 65 as now devised by me the lid is hinged to or upon a pivot common to said cross-bar, and the latter is secured to the lid, and at its outer end it is secured for closing by a suitable swinging link or stirrup, thus enabling the bar 70 and lid to be swung to and fro together without changing their relations to each other, and also enabling all of said parts, with the dip-pipe, to be integrally removed from the main. The frequent clearing of the ascension-pipes 75 also increases the liability of injury to the dip-pipe valves as heretofore organized by the contact therewith of the heavy tools of the workmen while engaged on top of the main. As shown in my said prior Letters Patent, the 80 stems of the dip-pipe valves have heretofore extended upward through the top of the main, and they were therefore specially liable to be bent or twisted by accidental blows from the tools used for clearing; and another object of 85 my invention is to obviate said liability of injury by so organizing the dip-pipe valves as to leave the top of the main wholly unobstructed, and to so locate their stems as to render them practically secure from injury. 90

The excessive development of tarry matters renders dip-pipe valves as heretofore constructed specially liable to derangement at their seats, because of the extraordinary deposit thereon of more or less solid matters, 95 rendering it difficult to obtain the requisite gas-tight joint when the dip-pipe lids are removed; and another object of my invention is to obtain a gas-tight joint regardless of the presence of such hitherto obstructive matters; 100 and I accomplish this and the protection of the valve-stem, and also obtain an unobstructed surface on top of the main for the convenience of workmen in clearing the ascension-pipes,

by the combination, with the dip-pipe, of a self-clearing valve provided with a horizontal valve-stem, which projects through the front side of the main.

5 To more particularly describe my invention, I will refer to the accompanying drawings, in which—

Figure 1 is a top view of a portion of a hydraulic main containing my improvements. 10 Fig. 2 is a lateral vertical section of the hydraulic main on line *x*, Fig. 1. Fig. 3 is a front view of a portion of the main with the dip-pipe valve-stem and its operating-lever removed. Fig. 4 is a horizontal section of the 15 dip-pipe and a portion of the front of the main on a line with the stem of the dip-pipe valve.

As heretofore, the hydraulic main *A* is located above one or more series or "benches" of retorts, and it internally communicates with 20 each retort by way of an ascension-pipe, *B*, and each of the latter terminates at its top within a dip-pipe, *C*, having its lower end immersed in the water with which the hydraulic main is charged for sealing purposes.

25 It will be seen that the ascension-pipe *B* passes through the bottom of the main and closely adjacent to its pocket *A'*, into which the tarry matters gravitate. As here shown, the said pocket is formed by making the hydraulic main deeper at its rear side than at 30 the front, and while I prefer that said pocket be rectangular in cross-section, as shown, similar results will accrue if the bottom of the main should be inclined downward from front to rear, as in both cases the tarry matter will gravitate to the lowest portion of the main. 35 However said pocket *A'* may be formed, I make provision for the removal of the tarry matter by means of draft-pipe *a*, communicating with said pocket at or near its bottom, and also by properly-guarded hand-holes *a'* in the rear side of the main, above the pocket. The heat from the ascension-pipe *B*, leading directly from a retort, maintains the 40 tarry product in a proper condition for ready 45 removal.

It is to be understood that the tarry by-products of retorts operated under extraordinarily high temperatures are of much greater 50 specific gravity than similar products incident to the employment of ordinary lower temperatures, and therefore the value of the pocket will be obvious as a means for accumulating the heavy tarry matters into such a position 55 within the main as will render them capable of convenient removal, and also so as to leave the surface fluid in the main in a desirably limpid condition, so as to enable gas to readily pass from the retort through the fluid seal 60 into the main should there be any delay in opening the dip-pipe valve after the closing of the retort.

65 The pendent dip-pipe *C*, as here shown, descends through the top of the main, and is supported thereon by means of a flange and secured by bolts, as illustrated in my prior Letters Patent hereinbefore referred to, and al-

I though said pipe has a removable lid, *c*, somewhat like that shown in said Letters Patent, said lid is now mounted in a novel manner, 70 and its seat is also materially improved. As here shown, the lid *c* is hinged to a pivot, *c'*, which is also common to the clamp-bar *c''*, and this latter, near its free or outer end, occupies a vertically-slotted bolt, *c'''*, tapped into 75 the lid, so that, although the clamp-bar is separately pivoted, it cannot be thrown rearwardly independently of the lid.

In lieu of the slotted bolt *c'''* for connecting the clamp-bar and lid, the clamp-screw *c''* and lid may be connected by a ball-and-socket joint at the lower end of the screw, in a manner well known.

The clamp-screw *c''* is tapped through the clamp-bar, so that its lower end bears centrally 85 upon the lid. The outer end of the clamp-bar is held for clamping by a pivoted slotted link or stirrup, *c'*. In said prior patent I show and describe the lid as having a beveled edge and the dip-pipe as having a mouth or lid seat of 90 corresponding beveled form, and although I employ the same beveled edge on the lid, I now employ therewith a sharp-edged seat, *d*.

It is well known that more or less solid tarry 95 matters are liable to accumulate at the seat of the lid, and that they are liable to be unequally distributed thereon, which renders it difficult for a gas-tight joint to be obtained with the correspondingly-beveled edges shown and described in my said prior Letters Patent. With 100 the sharp-edged seat a gas-tight joint is readily obtained, because it cuts and clears its way to a good bearing with the lid, and if any tarry matters should adhere to the edge of the lid, or to the seat, they really contribute as aids to 105 a gas-tight condition, instead of preventing it, as with the said prior construction of lid and seat. In some cases I reverse the positions of the sharp and the beveled edges, locating the latter at the seat and making the edge of the 110 lid sharp, so as to produce the same clearing effect, and it is obvious that with the seat thus beveled, instead of sharp, it is less liable to be bruised or indented by contact therewith of the tools used for clearing out the ascension- 115 pipe.

I am of course well aware of my prior use of the beveled edge and the sharp edge in connection with retort-lids, as illustrated in my prior Letters Patent No. 137,704, April, 1873; 120 but I know of no prior dip-pipe lid hinged or pivoted and combined with the clamp-bar, the clamp-screw, pivoted link, and slotted bolt, or equivalent connection, and enabled to secure a gas-tight joint by means of the coincident 125 beveled and sharp edges, as shown and described.

In my aforesaid prior Letters Patent No. 247,386 I show and describe a dip-pipe valve located on the inner side of the dip-pipe and 130 arranged to slide vertically, the valve-stem extending upward through the top of the main or the flange of the dip-pipe and connecting with a lever, by which said valve is opened

and closed. As hereinbefore indicated, the accumulation of obstructive matters materially interferes with the proper operation and closure of such a sliding valve or gate, and the extension of the valve-stems above the top of the main exposes them to frequent injury.

It will be seen that my present dip-pipe is rectangular in cross-section, and I have selected this form because of the greater facility with which the seat *e* of the dip-pipe valve *D* can be applied to a flat surface. It is practicable, however, to apply such a valve-seat to either a concave or a convex surface by providing for the seat a back plate which conforms to the surface to which the valve-seat is to be attached, and therefore the dip-pipe may be round, if desired. The said seat *e* is provided with a sharp annular edge, and it is shown to be integral with its back plate, *e'*, bolted to the dip-pipe, and it has a yoke, *e''*, affording a slide-bearing for the inner end of the valve-spindle *e'*, which, at its front end, projects through a stuffing-box mounted in the front wall or side of the hydraulic main. The self-clearing valve *D* has an annular beveled edge, which engages with the sharp edge of the seat *e*, causing the latter to cut through any tarry matters which may be deposited on the seat or valve, and thereby to secure a gas-tight joint. For the best results I make the valve and seat of metal varying in hardness—as, for instance, one of cast-iron and the other of soft or wrought iron. The beveled edge may be located on the seat, and the valve may be provided with a sharp front edge, and an equally-desirable self-clearing capacity will be obtained. Rings having a sharp edge may be detachably applied either to the valve or seat, for convenient renewal. The valve is moved to and from its seat by means of a bell-crank lever, *f*, pivoted to a bracket, *f'*, secured to the top of the main, and also pivoted by a ball and slotted joint to an adjustable head, *f''*, on the outer end of the sliding valve-stem.

If desired, the valve and stem may be rotative and moved to and fro by a screw-thread in a well-known manner. It will be seen, however, the valve and seat may be constructed, that the valve stem or spindle is wholly protected from injury while the workmen occupy the top of the hydraulic main, and that the top of the latter is practically un-

obstructed, thus greatly facilitating the clearing of the ascension-pipes, and it is obvious that the self-clearing valve can at all times be relied upon to obtain a gas-tight joint when the dip-pipe lid is removed.

I am of course aware that retorts have been heretofore cut off from the main by means of valves located below the main, and therefore the stems of such valves were not exposed to injury from workmen when on top of the main; but in such cases the valves are located in the ascension-pipes, and, if not opened simultaneously with the closing of the retorts, dangerous or objectionable pressures are liable to be induced, whereas with the dip-pipe and its valve a relief from pressure is afforded by way of the water-seal at the foot of the dip-pipe, thus rendering it important that the valve should be within the hydraulic main, and consequently necessary that its stem or spindle should project therefrom.

Having thus described my invention, I claim as new and desire to secure by Letters Patent—

1. The combination, with a hydraulic main provided with a pocket, of a pendent dip or sealing pipe and an ascension-pipe passing through the bottom of said main and adjacent to said pocket, substantially as described, whereby said pocket will receive the gravitating tarry products, and the latter be maintained at a temperature favorable to their deposit therein and removal therefrom, as set forth.

2. The combination, with the hydraulic main, of the flanged dip-pipe, the dip-pipe lid hinged to the flange of said dip-pipe, the coincident beveled and sharp edges for securing a gas-tight joint between pipe and lid, the clamp-bar hinged to said flange and connected to the lid, the pivoted link or stirrup, and the clamp-screw, substantially as described.

3. The combination, with the hydraulic main and dip-pipe, of the dip-pipe valve and seat having the coincident beveled and sharp edges for securing a gas-tight joint between said valve and its seat, and a horizontal valve-stem projecting through the side of the main, substantially as described.

GEO. A. McILHENNY.
